UNITED STATES PATENT OFFICE.

FRANK LUISA AND JAMES DI MATTEO, OF NEW YORK, N. Y.

TWIN-LABEL PUNCHER.

Application filed April 3, 1925. Serial No. 20,330.

This invention relates to improvements in label cutters, and it is the principal object of my invention to provide a label cutter or punching device for cutting a double stack of 5 labels from sheets in one operation, and for simultaneously removing the waste material by means of a specially constructed cutter adjustable and working on a fibrous base.

Another object of the invention is the provision of a means for adjusting the cutting or punching devices relatively to said waste remover and to said fibrous plate.

A further object of the invention is the provision of a waste remover of peculiar construction adapted to be adjusted and effectively preventing the clogging of the apparatus and the hollow punching tools by the waste paper cut from the sheets from which the labels are punched.

20 These and other objects and advantages of my invention will become more fully apparent as the description thereof proceeds, and will then be specifically pointed out in the appended claims.

25 In the accompanying drawings, forming a material part of this disclosure:

Figure 1 is a front elevation of a label-cutting device embodying the improved features constructed according to the present 30 invention.

Figure 2 is a rear end view thereof.

Fig. 3 is a bottom plan view of the cutter constructed according to the invention.

Fig. 4 is a cross-section on line 4—4 of 35 Figure 3.

Fig. 5 is a modified form of waste remover in side elevation.

Fig. 6 is a bottom plan view of a modification of the cutting apparatus.

40 Fig. 7 is a fragmentary sectional view of a waste remover adjusting and operating means.

A machine of suitable construction including a cross-head 10 to which the hollow suitably shaped cutting dies or plunger-knives 11 and 12 are secured by means of a boss 13, has attached thereto the pitman 14 operated from a crank shaft 15, journaled in bearings 16 and carrying at one end the fly-wheel 17.

50 The entire so far described mechanism is mounted on a base 18.

The hollow cutting dies 11 and 12 are mounted in any suitable manner as for instance described in our co-pending applica-

tion, Ser. #19,233, filed March 30, 1925, and 55 are equipped with superposed adjustable discharge chutes 19 and 20.

The waste remover in this form of our invention is supported upon a base 21, and comprises a plate 22 of fibrous or other suitable material having lateral flanges 23, 24 to the outer edges of which shoes 25, 26 are attached, which glide in grooves 27, 28 of the base plate 21. These shoes are provided with elongated slots 29, 30, 31 and 32 in 60 which the adjusting screws 33 are arranged adapted to be operated by means of wing nuts 34 or the like. The lower ends of the shanks 35, 36 of the waste remover blade 37 of substantially stretched or elongated 65 U-shape are secured to the shoes 25, 26 between each pair of openings therein.

In the form of waste remover blade shown in Figure 5, the blade 38 has one foot 39 only secured, as above described in the 75 fibrous plate flange on the bottom plate.

In the form of the invention illustrated in Figures 6 and 7, the fibrous plate 40 has flanges 41, 42 formed therewith to which the shoes 43, 44 are secured, having comparatively small slots 45, 46 therein and longer elongated slots 47, 48 formed therewith, the inner side edges of which are formed into racks 49 and 50 respectively, adapted to be engaged by gears 51, 52 on 80 shafts 53, 54, which carry also larger gears 55, 56 in mesh with worms 57, 58 on a transverse shaft 59 having an operating handle 60 at one end. The shoes 43, 44 glide in grooves 61, 62 in the base-plate 63, and pins 64, 65 travel within slots 45, 46 to limit the 85 movements of plate 40.

The waste remover blade 66 in this form, also of a stretched U-shape in side elevation, has its foot parts 67 attached to channeled 90 foot flanges 68 having an inner thread adapted to be engaged by a gear 69 on a stub-shaft 70 which carries within a chamber 71 of base plate 63 a worm wheel 72 in mesh with a worm 73 at the inner end of a 95 shaft 74 extending through the side of the base-plate 63, carrying a knob 75. A great mechanical advantage exists between the worm pinions, worm wheels, and the gears, so that the worm pinions are turnable to 100 move the fibrous plate, while conversely a great mechanical disadvantage exists, and trying to force to move the fibrous plate

will result in parts breaking rather any motion, whereby an adjustable self holding feature is accomplished.

From the above description the operation of our device will be entirely clear, if it is desired to adjust the waste remover blade and the fibrous plate, this can be done by the proper operation of the shoes 25, 26 by the manipulation of wing nuts 34 in the form Figure 3, or by the proper manipulation of knob 75 in the form illustrated in Figures 6 and 7. The plate in this form is independently adjustable by means of the manipulation of handle 60.

15 It is to be understood that while we have shown the principal embodiment of our invention in the drawings, by way of example, changes may be made such as fall within the scope of the appended claims without 20 departure from the spirit of our invention.

Having thus described our invention, what we claim as new and desire to secure by Letters Patent is:

1. A label punching machine comprising 25 a pair of hollow punching dies, a fibrous plate adjustably arranged beneath said dies, and a waste remover blade on said plate, and means for adjusting the relative positions of said fibrous plate and said waste 30 remover plates.

2. In a label punching machine of the class described, a base plate, a pair of hollow adjustable punching dies above said plate, a fibrous plate on said base plate, 35 means for adjusting the relative positions of both plates, a waste remover blade, and means for adjusting the position of said blade relatively to said plate and punching dies.

40 3. In a label punching machine of the class described, a grooved base-plate, a fibrous plate adapted for displacement on said base, shoes on said plate sliding in the grooves of said base, and means for locking the parts in their relative adjusted positions, and an adjustable waste remover blade on said fibrous plate adapted to be operated and locked by said displacing means.

45 4. In a label punching machine having a pair of punching dies, a base plate having grooves formed therein, a fibrous plate slidably arranged above said base plate, shoes formed with said fibrous plate adapted to 50 slide in the grooves of said base plate, means for adjusting the relative positions of both plates, and a waste remover blade guided in said shoes, and means for locking it in any of its adjusted positions.

5. In a label punching machine, a base 60 plate having grooves formed therein, a fibrous plate having shoes sliding in said grooves, a waste remover blade extending across said fibrous plate and having its ends attached to said shoes, said shoes being 65 formed with elongated apertures having inner racks on one side, gears in mesh with said racks, shafts for said gears, worm wheels on said shafts within chambers formed in said base plate, worm pinions in 70 engagement with said worm wheels, a shaft carrying said worm pinions and extending beyond the edge of said base plate, and a knob at the outer end of said rod, whereby an adjustment and holding of waste 75 remover blade and fibrous plate is accomplished by the mechanical disadvantage of said worm pinions to gears.

6. In a label punching machine of the class described, a grooved base-plate, a fibrous plate slidably arranged above said base-plate, shoes attached to said fibrous plate adapted to slide in the grooves of said base-plate, said shoes having pairwise arranged larger and smaller slots, racks on 85 the inner side edges of said larger slots, gears in mesh with said racks shafts for said gears, larger gears on said shafts, worms in engagement with said larger gears, a transverse shaft for said worms, and a handle at one end of said shaft for displacing said fibrous plate relatively to the base-plate by the operation of gears on said shaft.

7. In a label punching machine a base-plate having grooves formed therein, a fibrous plate having shoes sliding in said grooves, means for displacing said shoes and fibrous plate relatively to said base plate and holding the parts in their adjusted positions, and a waste remover blade 95 extending across said fibrous plate having its angular ends attached to channeled foot flanges formed with inner racks, gears in mesh with said racks, a shaft for said gears, worms on said shafts within a chamber 100 formed in the base-plate, a worm in engagement with said worms, a rod carrying said worm and extending beyond the edge of said base-plate and a knob at the outer end of said rod for allowing an adjustment of 105 said waste remover blade, and means for holding the parts in their relative adjusted positions.

In testimony whereof we have affixed our signatures.

FRANK LUISA.
JAMES DI MATTEO.
